Attest

United States Patent Office.

R. WARD, OF EDINBURG, INDIANA.

Letters Patent No. 106,521, dated August 16, 1870.

STOVE-GRAVE.

The Schedule referred to in these Letters Patent and making part of the same.

To all whom it may concern:

Be it known that I, R. WARD, of Edinburg, in the county of Johnson and in the State of Indiana, have invented certain new and useful Improvements in Stoves and Furnaces; and do hereby declare that the following is a full, clear, and exact description thereof, reference being had to the accompanying drawing and to the letters of reference marked thereon.

The nature of my invention consists in the application, to stoves or furnaces, of a curved plate provided with holes or perforations, and with lips projecting downward from said perforations, to answer the purpose of a grate.

In order to enable others skilled in the art to which my invention appertains to make and use the same, I will now proceed to describe the manner in which the same is or may be constructed, referring to the annexed drawing, which forms a part of this specification, and in which—

Figure 1 is a plan view, and

Figure 2, a longitudinal vertical section.

A represents a plate of any suitable material, the ends *a a* of which are horizontal or straight, but the main portion is curved downward.

The curved portion of the plate A is perforated with any number and size of holes, which are punched through the metal from above, so that the portions of the metal punched out project downward, forming inclined lips *b b* under the plate, as seen in fig. 2.

This plate is placed a suitable height above the bottom of stove or furnace to admit a supply of air between the bottom of stove and said plate, which will keep the bottom of the stove and plate from heating,

and supply air through the punched or perforated holes.

The plate may require a support under it in case of heavy wood or coal thrown in on it, which can be supported by a bar of iron placed around it or across it on the under side, as it may require.

The plate should fit in tight, so that air can only pass up through the perforations; then the chimney or stove-pipe will cause a suction of air, which will strike the wood and fire under part of wood resting on said plate, which will cause a bright blaze to shoot out opposite the holes, and cause the fire to become hotter and brighter.

This improvement can be made to be used in stoves almost of any kind that are used at the present time.

The draught is operated by the usual means, such as dampers or slide on the doors of the stove.

Having thus fully described my invention,

What I claim as new, and desire to secure by Letters Patent, is—

1. The curved plate A, provided with a number of perforations, each having lips *b b*, extending below the plate, substantially as shown and described.

2. In combination with a stove or furnace of any description, the curved perforated plate A, having lips *b b*, projecting below the plate, substantially as and for the purposes herein set forth.

In testimony that I claim the foregoing, I have hereunto set my hand this 6th day of January, 1869.

R. WARD.
